ABSTRACT

An electronic circuit system for triggering the successive injectors of an internal combustion engine, chiefly a Diesel engine. A first circuit controlled by the rotation of the engine provides for the starting of saw-tooth voltage wave, the length of the rising slope of which depends on the speed of rotation while the peaks of said pulses trigger the injections which last until the end of the pulse. A delay for said triggering is advantageously obtained by the difference between the time constants of two flip-flops the first of which is constant while that of the second flip-flop depends on the operative parameters of the engine, the end of the injection being defined by the end of the signal produced by the first flip-flop.

**ELECTRONIC CONTROL SYSTEM FOR THE INJECTORS
OF INTERNAL ENGINES**

The present invention has for its object an arrangement for electronically controlling injectors in internal combustion engines wherein each injection is triggered by a pulse generator controlled by the rotation of the engine.

In order to obtain a satisfactory operation of an engine, whether it is equipped with mechanically controlled injectors or, as in the case of the present invention, with electronically controlled injectors, it is often necessary to obtain a modification in the starting point of the injection depending on the speed of rotation of the engine and/or on the load. It has previously been proposed to modify said starting point in accordance with the speed of rotation by centrifugally controlled means for mechanically as for electronically controlled injections. With electronically controlled injectors, voltage generators have previously been used, operating as a function of said speed of rotation, the voltage obtained defining a lag for the injection with reference to a signal produced by a pulse generator associated with the rotation of the engine, which lag diminishes with an increase of the speed of rotation; said pulse generator is designed in a manner such that the lag becomes zero for a maximum speed of rotation, that is the lead of the injection with reference to the upper idle center becomes a maximum. By providing furthermore a control of the beginning of the injection by the load, it is possible to adjust the injection in accordance with the requirements of each engine.

Although such an arrangement is only of slight interest for spark controlled ignition engines in association with an indirect injection, it becomes essential in the case of Diesel engines since in this case the beginning of the combustion is defined by the beginning of the injection, taking into account the delay required for ignition in accordance with physical and chemical conditions and also with the geometrical structure of the engine.

The above-mentioned devices are however somewhat bulky and subject to wear as is the case with all mechanical or electromechanical arrangements.

The present invention has for its object to eliminate said drawbacks and it has more particularly for its object an electronic control system for the injectors of internal combustion engines, wherein the injection is triggered by a pulse generator controlled by the rotation of the engine. According to the present invention there is obtained a lag for the injection by means of electronic delaying means controlled by the rotary speed of the engine, said means including a circuit generating a saw-tooth voltage the rise of which is triggered by pulses fed by said pulse generator while its peak triggers an injector, the slope of said saw-tooth voltage being such that, according to the spacing in time of the generated pulses, that is according to the rotary speed of the engine, the spacing between the peaks and troughs of said saw-tooth voltage is reduced together with the lag of the injection when the rotary speed increases. Complementary electronic delay means may be provided which operates under the control of the engine load of the engine and which includes two flip-flops triggered simultaneously by a signal controlled directly or indirectly by the rotation of the engine. The first flip-flop produces a rectangular signal of a constant duration while the second flip-flop produces a rectangular signal the duration of which varies with the load of the engine. The flip-flops act on a common circuit designed in a manner such that it produces a rectangular signal for controlling the injection, the duration of which is equal to the difference between the durations of the signals produced by said first and second flip-flops. The injection begins at the end of the signal produced by the second flip-flop and ends together with the signal produced by the first flip-flop.

By way of example and in order to further the understanding of the description, the accompanying drawings are provided in which:

FIG. 1 is a block diagram of the arrangement according to the invention;

FIG. 2 sets forth graphs showing the succession of signals produced by the different sections of the arrangement illustrated in FIG. 1; and

FIG. 3 is a schematic diagram of an electronic circuit executed in conformity with the invention.

FIG. 4 illustrates the succession of signals produced by the different sections of the arrangement illustrated in FIG. 1 corresponding to one value of rotary speed of the engine.

FIG. 5 illustrates the succession of signals produced by the different sections of the arrangement illustrated in FIG. 1 corresponding to a higher value of rotary speed of the engine than illustrated in FIG. 4.

As illustrated in FIG. 1, pulse generator A controlled by the rotation of the engine, which is not illustrated, sends a pulse to the saw-tooth voltage generator B, said saw-tooth voltage being transformed at C into positive rectangular signals which are cut off during a period T_0 (FIG. 2) each time a pulse is applied to the saw-tooth generator B and which start at each peak of the saw-tooth voltage. The circuit C simultaneously triggers flip-flops D and E each time it produces a rectangular signal. The flip-flop D produces a rectangular signal of constant duration T_1 , while the flip-flop E produces a rectangular signal of duration T_2 , the length of which depends on various operative parameters of the engine which parameters are transmitted through the sensors a, b and c. The flip-flop signals T_1 and T_2 are applied to a common circuit F producing a rectangular signal for controlling the injection and the duration of which, T , is equal to the difference $T_1 - T_2$ defining the duration of injection. Said signal of duration T is transmitted to a circuit G distributing the signals T into the injectors H in accordance with the predetermined order of injection.

FIG. 2 illustrates the various signals produced by the successive elementary circuits of FIG. 1. The pulse A produces transient pulses the spacing of which depends on the rotary speed of the engine. The pulses illustrated in interrupted lines correspond to a higher speed of rotation, which means a shorter interval between successive pulses. Each pulse triggers saw-tooth voltage generator B. Said saw-tooth voltage pulses increase linearly during a period T_0 until a well-defined peak value is obtained. At this moment, the circuit C begins producing a rectangular signal T_0 and the voltage produced by the generator B decreases linearly until the next pulse received from pulse generator A cuts off the rectangular signal produced by the circuit C.

As illustrated in dotted lines, the interval between two successive pulses decreases when the rotary speed increases. Consequently the saw-tooth voltages cannot decrease as far as for lower speeds. Thus, the duration T_0 , is shorter, since the peak of the saw-tooth voltages does not vary. The duration T_0 corresponds to the lag required for injection as a function of the speed of rotation, with reference to the pulse produced by the generator A. This lag decreases rapidly for increasing speeds by the shortening of the rising and falling slopes of the saw-tooth voltage.

Since the pulses produced by the pulse generator A are obtained clearly before the upper idle centers of the engine pistons, the circuits B and C produce signals which lead with reference to the upper idle centers, the lead measured by the rotary angle travelled over by the crankshaft varying with the speed of rotation in accordance with the lengths of the voltage slopes.

It should be noted that it is possible to utilize only to the circuits B and C with an electronic injection-controlling system when it is merely desired to time the injections under the control of the speed of rotation.

However and more particularly in the case of Diesel engines, it is often of interest, for a given speed of rotation, to end the injection at a predetermined time, whatever may be the duration of the injection, that is whatever may be the amount of fuel to be injected. To obtain such a result, the invention utilizes two flip-flops, D and E, as mentioned hereinabove. The first flip-flop D produces a rectangular signal of constant duration T_1 while the second flip-flop E produces a rectangular signal of variable duration T_2 . The cir-

cuit F fed by both flip-flops produces a rectangular injection-controlling signal of a duration $T=T_1-T_2$, the beginning of which coincides with the end of the second rectangular signal of duration T_2 , while its end is controlled by the end of the first rectangular signal of duration T_1 . It is thus apparent that with the arrangement according to the invention, there is obtained a lag of the injection with reference to the triggering pulse produced by the pulse generator A, equal to T_0+T_2 . T_0 depends on the speed of rotation while T_2 is a function of the load on the engine.

The injection lag T_0 plus T_2 is illustrated in FIGS. 4 and 5. T_0 varies as a function of the rotary speed of the engine, and T_2 varies as a function of the load on the engine. Referring to FIG. 4, a series of timing pulses having a predetermined frequency which corresponds to one rotary speed of the engine, are illustrated on line A. FIG. 5 illustrates a corresponding series of timing pulses (line A') having a predetermined frequency of about twice the frequency of the pulses illustrated in FIG. 4, thus representing the increase in the rotary speed of the engine. As shown in FIGS. 4 and 5, each timing pulse triggers the saw tooth voltage generator which generates the saw-tooth voltage illustrated on lines B and B'. The peak of the saw-tooth voltage does not vary. Thus, by comparing the respective saw tooth voltages of FIGS. 4 and 5, it can be seen that the rise time for the respective saw-tooth voltages decreases as the frequency of the pulses increases, corresponding to an increase in the rotary speed of the engine. The rise time of the saw-tooth voltages is represented by T_0 and T_0' , respectively.

The first rectangular pulse generating means D and the second rectangular pulse generating means E are triggered each time the saw tooth voltage reaches its peak. The first rectangular pulse generated by the first generating means has a predetermined duration represented in FIGS. 4 and 5 by T_1 and T_1' , respectively. The second rectangular pulse generated by the second generating means has a duration which varies as a function of at least one engine parameter such as the load on the engine. These durations are represented by T_2 and T_2' , respectively. The durations T_2 and T_2' are shown as being unequal, thus corresponding to the different loads on the engine. As the load on the engine decreases, the time T_2 decreases.

Referring to line F of FIG. 4, the actuating pulse, having a duration represented by T , begins at a variable time interval equal to T_0 plus T_2 after each timing pulse generated by the pulse generator, and the actuating pulse ceases at the end of the first rectangular pulse from the first generator means which has a fixed width or duration T_1 . The time T_0 is variable and is determined by the frequency of the timing pulses generated by the pulse generator, which is a function of the rotary speed of the engine. As noted above, the time T_2 varies as a function of at least one of the engine parameters such as the load on the engine. Thus, the ignition lag or elapsed time T_0 plus T_2 between each timing pulse of the pulse generator and the corresponding actuating pulse, having a duration T , is a function of both the rotary speed of the engine and the load on the engine. This can be clearly seen by comparing the ignition lag of FIG. 4 with the ignition lag T_0' plus T_2' illustrated in FIG. 5. Also, the duration of the actuating pulse, T and T' , respectively, increases as the load in the engine increases, since T_2 and T_2' are decreasing.

FIG. 3 illustrates the electronic circuit incorporating the circuits B,C,D,E and F shown in block diagram in FIG. 1. The saw-tooth voltage generator B comprises a programme-controllable uni-junction transistor T_2 and a condenser 3 charged under constant current conditions through a resistance 17, a transistor T_1 and a diode 19, while it is discharged under constant current conditions through the transistor T_8 and the resistance 20. The base of the transistor T_1 is maintained at a predetermined adjustable voltage by a voltage-divider constituted by the resistances 5 and 7 connected by a potentiometer 6, while the electrode controlling the uni-junction transistor T_2 is maintained at another voltage defined by a

75 voltage-divider comprising series resistances 15 and 16. The point connecting the anodes of the diode 19 and of the programme-controllable uni-junction transistor T_2 with the collector of the transistor T_1 is grounded through the collector-emitter circuit of the transistor T_4 while the base of transistor T_4 forms the input E of the saw-tooth voltage generator to which the signal produced by the pulse generator A is applied. Said input E is grounded through the resistance 23. The control electrode of the uni-junction transistor T_2 is connected with the base of another transistor T_{10} through a resistance 25 forming part of the voltage-divider constituted by the resistances 27, 26, 25 and 24. The collector-emitter circuit of said transistor T_{10} is connected in parallel with a condenser 11 between the point connecting further resistances 21 and 22 and ground. The resistances 21 and 22 form with a grounded potentiometer 9 a further voltage-divider, the slider of said potentiometer 9 defining the voltage applied to the base of the transistor T_8 so that said voltage may assume a predetermined adjustable value.

10 The circuit C includes transistor T_{12} the emitter-collector circuit of which is connected in series with the resistance 28 between the supply of voltage and ground, while its base is connected with the point connecting the resistances 26 and 27. The collector of the transistor T_{12} forms the output S of the circuit C. The output signals are transmitted through the diode 29, the condenser 31 and diode 32 to flip-flop E and diode 33 to flip-flop D. In order to discharge the condenser 31 after a positive signal has charged it, the point connecting the diode 29 with said condenser 31 is grounded through a resistance 30.

15 The flip-flops E and D each comprises a programme-controllable uni-junction transistor, T_{37} or T_{49} connected in series with variable resistance 38 and with fixed resistance 48, respectively. The cathodes of said programme-controllable uni-junction transistors are connected with the bases of the corresponding transistors T_{41} and T_{52} . The points connecting the resistances 38 and 48 with the anodes of the uni-junction transistors T_{37} and T_{49} are grounded respectively through the collector-emitter circuits of the corresponding transistors T_{34} and T_{46} and through the corresponding condensers 36 and 47 in parallel with the latter. The bases of the transistors T_{34} and T_{46} are grounded through the resistances 35 and 45 respectively and are connected with the cathodes of the corresponding diodes 32 and 33 fed by the circuit C through the condenser 31. The electrodes controlling said uni-junction transistors T_{37} and T_{49} are maintained at a predetermined voltage by the voltage-dividers constituted respectively by the series resistances 39-40 and 50-51.

20 The circuit F producing the rectangular injection-controlling signals is constituted by the transistors T_{41} and T_{52} , already referred to as connected through their bases with the cathodes of the corresponding programme-controllable uni-junction transistors T_{37} and T_{49} . The collector-emitter circuit of each of said transistors T_{41} and T_{52} is connected in series with the corresponding resistances 42 or 53 between the voltage supply and ground. A connection between the collector of the transistor T_{41} and the base of the transistor T_{52} is provided through a diode 43 and a resistance 44. The point connecting the collector of the transistor T_{52} with the corresponding resistance 53 forms the output S for the rectangular signal controlling the injection and the duration of which is T.

25 65 The operation of the circuit is as follows:

When the voltage supply is applied and in the absence of any signal at the input E of saw-tooth voltage generator B, the programme-controllable uni-junction transistor T_2 is conductive and is fed with a current the value of which is defined by the resistance 17 and the conductance of transistor T_1 , as a function of the voltage applied to the base of said transistor T_1 . The anode and the control electrode of the uni-junction transistor T_2 are substantially at zero voltage so that no charge can be applied to the condenser 3. Similarly, the point connecting T_8 resistances 25 and 26 is practically at zero voltage

whereby the transistor T12 remains conductive. However, by reason of the presence of the condenser 31, this has no influence on the flip-flops D and E. The point connecting said resistances 25 and 26 being at zero voltage, transistor T10 is nonconductive and a predetermined voltage is applied to the base of transistor T8 as defined by the voltage-divider constituted by the resistances 21 and 22 and by the position of the slider of the potentiometer 9. This results in transistor T3 conducting and condenser 3 remains in a discharged condition.

As to the flip-flops E and D, the uni-junction transistors T37 and T49 are conductive since the transistors T34 and T46 are non-conductive, while the condensers 36 and 47 are discharged and the electrodes controlling said program-controllable single-junction transistors T37 and T49 are subjected to a voltage which is substantially equal to zero. Consequently, the transistors T41 and T52 are both conductive so that the output S of the circuit F is substantially at zero voltage.

If a short pulse is now applied at the input E of the saw-tooth voltage generator B, transistor T4 becomes momentarily conductive and the voltage applied to the anode of the transistor T2 is returned substantially to zero and said transistor T2 is cut off. When the pulse applied to the input E terminates, the transistor T4 is nonconductive again and a constant charging current is established, as defined by the resistance 17 and the conductive transistor T1, whereby the voltage on the anode of the uni-junction transistor T2 rises linearly. During this time, the control electrode of said uni-junction transistor T2 is at a voltage defined by the voltage divider constituted by the resistances 15 and 16, said voltage also being applied simultaneously to the base of the transistor T10 making it conductive. This results in the voltage at the point connecting resistances 21 and 22 and on the base of transistor T8 becoming zero. Transistor T8 is then cut off. The transistor T12 is also cut off by the voltage applied to its base and the voltage at the output S of the circuit C is returned to zero, this having however no effect on the flip-flops D and E.

When the voltage across the terminals of the condenser 3 reaches a predetermined value, depending on the voltage applied to the control electrode of the uni-junction transistor T2, the latter again suddenly becomes conductive. At this moment, the voltage on the control electrode of the transistor T2 becomes substantially zero and the transistor T12 again becomes conductive while transistor T10 is again cut off. Consequently, condenser 11 is charged and the voltage applied to the base of transistor T8 rises so that said transistor T8 becomes conductive. Therefore, during the period during which the transistor T10 is cut off, and transistor T8 is conductive condenser 3 is discharged under constant current conditions through the transistor T8 and the resistance 20. The diode 19 prevents any discharge through the uni-junction transistor T2 or through the transistor T4. The discharge of the condenser 3 continues until a further pulse appears at the input E of circuit B.

At the moment at which the transistor T12 again becomes conductive, a positive pulse is transmitted to the bases of the transistors T34 and T46 through the diode 29, the condenser 31 and the corresponding diodes 32 and 33. Said transistors T34 and T46 then become momentarily conductive, which results in a return to zero of the voltage applied on the anodes of the uni-junction transistors T37 and T49 which are thus cut off. From this moment, condensers 36 and 47 are charged according to a time constant defined by their capacities and by the values of the resistances 38 and 48. The uni-junction transistors T37 and T49 being cut off, the transistor T41 is also cut off and this causes a voltage to be applied to the base of transistor T52 which is held in a conductive condition so that the output S of the circuit F is at zero voltage. However, since the time constants T1 and T2 of the flip-flops D and E are selected so that T1 is larger than or equal to T2, the transistor T37 becomes conductive before the transistor T49. When T37 becomes conductive, T41 will become conductive. At this moment, the point connecting the resistance 42 with the collector of the transistor T41 is returned to zero voltage

and the transistor T52 is cut off. When T52 is cut off the output at S rises sharply to a value determined by resistance 53 and the voltage supply. The output S remains at this voltage until T52 conducts again. This occurs at the end of the pulse of duration T1, when T49 and T52 conduct. The result is that a rectangular signal of a duration T equal to $T_1 - T_2$ appears at the output S of the circuit F.

The time constant of each of the flip-flops E and D is defined by the capacities of the condensers 36 and 47 and by the values of the resistances 38 and 48.

As a matter of fact, as long as the programme-controllable uni-junction transistors T37 and T49 are cut off, condensers 36 and 47 are being charged, but as soon as the voltage across the said condensers 36 and 47 reaches a predetermined value, defined by the voltage applied to the electrodes controlling the corresponding uni-junction transistors T37 and T49, the latter suddenly conduct and cause transistor T41 and T52 to conduct, the injection-controlling signal at S returning to zero voltage as soon as transistor T52 again becomes.

This therefore produces a duration of the injection-controlling signal which is equal to $T = T_1 - T_2$ and its value may range between $T = 0$ and $T = T_1$. The modification in the duration of injection is obtained by a modification of T2 provided by the variable resistance 38 under control of the load on the engine, the timing of the end of the injection period remaining constant for a predetermined speed of rotation.

Turning to the saw-tooth voltage generator B, its cycle loading and discharging the condenser 3 is defined by the pulses applied to the input E. Now, since the slope of the rising voltage is defined by the current passing through the transistor T1, that is by the voltage applied to the base of the latter, while the slope of the falling voltage is defined by the current passing through transistor T8, that is by the voltage applied to the base of the latter, the time available for the charging and discharging is obviously shortened when the speed of rotation increases. Consequently, the difference between the peaks and troughs of the saw-tooth voltage decreases gradually with increasing speeds since, the duration of discharge of the condenser 3 decreases steadily. Therefore, the time T_0 elapsing from the moment of the application of the signal at the input E for charging the condenser 3 up to the peak of the saw-tooth voltage decreases when the speed of rotation increases. Consequently the duration T_0 is a function of the speed of rotation and according to the voltage slopes defining the charging and discharging of condenser 3, the time T_0 decreases rapidly with an increase in the speed of rotation. Since the angle θ measured in degrees defining the angular travel of the crankshaft beginning at the moment of the pulse produced by the pulse generator A and terminating at the end of the period T_0 is directly proportional to the rotary speed N of the engine and is inversely proportional to said duration T_0 , the following equation is true:

$$\theta = P N / T_0$$

P being a coefficient of proportionality. Therefore, it is possible to select the slopes of the saw-tooth voltage in a manner such that θ increases with the speed of rotation, remains constant when said speed is constant and decreases with said speed, this being of major interest since it corresponds to an increase of the lead with reference to the upper idle center when the rotary speed increases.

It should also be noted that the control electrode of the program-controllable uni-junction transistor T2 may be connected directly with the point joining the resistances 21 and 22, and transistor T10 and condenser 11 eliminated.

In such a case, the condenser 3 begins its discharge as soon as a positive voltage appears. In contradistinction, if transistor T10 and condenser 11 are retained, transistor T8 becomes conductive only after the charging of condenser 11. The latter case corresponds to FIG. 2, assuming a horizontal line extends across the rising and falling slopes of the saw-tooth voltage waves so as to separate said slopes.

It is therefore obvious that with simple static circuits having no moving parts, it is possible to obtain an arrangement

providing an adjustment of the delay of the injection with reference to a predetermined position of the crankshaft under control of the rotary speed and also control delay of the injection in accordance with the load on the engine, both adjustments being readily executed by means of potentiometers so as to take into account the type of engine incorporating the arrangement described.

I claim:

1. An electronic control system for electromagnetic fuel injectors in an internal combustion engine, comprising:

- a. a pulse generator for generating timing pulses spaced as a function of the rotary speed of the engine, the spacing between the timing pulses decreasing as speed increases;
- b. a saw tooth voltage generator for generating a saw tooth voltage in response to each of said pulses, the duration of said saw tooth voltage being dependent on the spacing between successive timing pulses, the time interval between each timing pulse and the peak voltage of the saw tooth voltage generated in response to the timing pulse being a function of the rotary speed of the engine, and
- c. means triggered by the peak voltage of each of said saw tooth voltages for producing actuating pulses for said electromagnetic injectors, whereby the time interval between a pulse generated by said pulse generator and the actuating pulse triggered by the peak voltage of the saw tooth voltage generated in response to the pulse is a function of the rotary speed of said engine.

2. The electronic control system set forth in claim 1 wherein said means for producing actuating pulses comprises:

- a. first rectangular pulse generating means for generating first rectangular pulses of predetermined width;
- b. second rectangular pulse generating means for generating second rectangular pulses the widths of which vary as a function of at least one engine parameter such as the load on the engine;
- c. means for simultaneously triggering said first and second rectangular pulse generating means in response to the peak voltage of each of said saw tooth voltages; and
- d. means for combining the outputs of said first and second rectangular pulse generating means for producing rectangular actuating pulses equal in width to the difference between the width of the first rectangular pulse and the width of the second rectangular pulse, each of said actuating pulses commencing at the end of each second rectangular pulse from said second rectangular pulse generating means and ending at the end of each first rectangular pulse from said first rectangular pulse generating means, whereby the time interval between a timing pulse generated by said pulse generator and the beginning of the actuating pulse corresponding to the timing pulse is a function of the rotary speed of the engine and the engine parameter, and the width of the actuating pulse is a function of the engine parameter.

3. A system as claimed in claim 2 wherein said saw-tooth voltage generator includes a condenser, a circuit for charging the condenser with an adjustable constant current, a circuit for discharging the condenser under adjustable constant current conditions, a programmable uni-junction transistor connected in parallel with said condenser and the control electrode of which is connected with the condenser discharging circuit, a voltage divider feeding said control electrode and adapted to render simultaneously conductive said uni-junction transistor and said condenser discharging circuit, the charging of the condenser being started by a pulse from said pulse generator rendering said uni-junction transmission nonconductive.

4. A system as claimed in claim 2 wherein said saw-tooth voltage generator includes a condenser, a circuit for charging the condenser with an adjustable constant current, a circuit for discharging the condenser under adjustable constant current conditions, a programmable uni-junction transistor connected in parallel with said condenser and the control elec-

trode of which is connected with the condenser discharging circuit, a voltage divider feeding said control electrode and adapted to render simultaneously conductive said uni-junction transistor and the condenser discharging circuit, a primary

5 transistor connected between the anode of the uni-junction transistor and ground and the base of which is connected with the pulse generator whereby it becomes momentarily conductive each time a pulse is applied to said base and the voltage applied to the anode of said uni-junction transistor is momentarily returned to zero so that said uni-junction transistor is cut off while the condenser begins its charging period.

6. A system as claimed in claim 2 wherein said saw-tooth voltage generator includes a condenser, a circuit for charging

15 said condenser with an adjustable constant current, a circuit for discharging said condenser under adjustable constant current conditions, a programmable uni-junction transistor connected in parallel with said condenser and the control electrode of which is connected with said condenser-discharging circuit, a voltage-divider feeding said control electrode and adapted to render simultaneously conductive said uni-junction

20 transistor and said condenser-discharging circuit, the charging of said condenser being started by a pulse from said pulse generator cutting off said uni-junction transistor, a voltage di- 25 vider defining the current in said condenser charging circuit, a further transistor the collector of which is connected with a point of said voltage divider, the emitter of which is grounded and the base of which is connected with the control electrode of said uni-junction transistor whereby said further transistor

30 is conductive when said uni-junction transistor is cut off and is non-conductive when said uni-junction transistor is conducting, a further condenser connected in parallel with the emitter-collector circuit of said further transistor whereby a lag is obtained between the cutting off of said further transistor and the moment at which said condenser-discharging circuit becomes conductive.

6. A system as claimed in claim 2 wherein said saw-tooth voltage generator includes a condenser, a circuit for charging the condenser with an adjustable constant current, a circuit

40 for discharging the condenser under adjustable constant current conditions, a programmable uni-junction transistor connected in parallel with said condenser and the control electrode of which is connected with said condenser discharging circuit, a voltage divider feeding said control electrode and adapted to render simultaneously conductive said uni-junction

45 transistor and the condenser-discharging circuit, the charging of said condenser being started by a pulse from said pulse generator cutting off said uni-junction transistor, a voltage-di- 50 vider defining the current in said condenser-charging circuit, a further transistor the collector of which is connected with a point of said voltage-divider, the emitter of which is grounded and the base of which is connected with the control electrode of said uni-junction transistor whereby said further transistor

55 is conductive when said uni-junction transistor is cut off and is non-conductive when said uni-junction transistor is conductive, a further condenser connected in parallel with the emitter-collector circuit of said further transistor whereby a lag is obtained between the cutoff of said further transistor

60 and the moment at which the condenser-discharging circuit becomes conductive, a grounded resistance, a still further transistor the emitter-collector of which is connected between the voltage supply and said grounded resistance and the base of which is connected with the control electrode of said uni-junction transistor, the point connecting said grounded resistance and said still further transistor being connected with said first and second rectangular pulse generating means to feed them with the rectangular signal passing through said

65 point as long as said uni-junction transistor is conductive.

7. A system as claimed in claim 2 wherein said first and second rectangular pulse generating means comprise respectively first and second flip-flops and said combining means includes a first and a second auxiliary transistor the bases of which are respectively connected with said first and second flip-flops, a resistance connected in the emitter-collector cir-

cuit of each auxiliary transistor, means for adjusting the time constant of said second flip-flop between zero and the value of the time constant of said first flip-flop, a diode connecting the collector of the auxiliary transistor connected with the second flip-flop, with the base of the auxiliary transistor connected with the first flip-flop and a connection adapted to tap said actuating pulses for the injectors off the collector of the auxiliary transistor connected with said first flip-flop.

8. A system as claimed in claim 7 wherein a programmable uni-junction transistor and a resistance connected in series between the voltage supply and the base of its associated auxiliary transistor, voltage-divider means for maintaining a predetermined voltage on the control electrode of said uni-junction transistor, a condenser, a further auxiliary transistor

the emitter-collector circuit of which is connected in parallel with said condenser between the anode of said uni-junction transistor and ground and the base of which is connected to said means for simultaneously triggering, so as to return to zero the voltage on the anode of said uni-junction transistor and thereby trigger said flip-flop, which returns to its initial condition when the voltage on said condenser reaches a value with reference to that on the control electrode of said uni-junction transistor to render it conductive.

5 10 9. A system as claimed in claim 7 further including a diode and a condenser connected in series between said means for simultaneously triggering and said flip-flops.
